BALL RETURN CASING OR THE LIKE

Richard G. Reineman, Covina, Calif., assignor to The Brunswick-Balke-Collender Company, Chicago, Ill., a corporation of Delaware

Application January 24, 1958, Serial No. 49,402

Term of patent 14 years

(Cl. D34—5)

Fig. 1 is a perspective view in elevation of the ball return casing;

Fig. 2 is a top plan view of the ball return casing; and

Fig. 3 is a side elevational view of the ball return casing.

The dominant features of my design are shown in full lines.

I claim:

The ornamental design for a ball return casing or the like, as shown and described.
